UNITED STATES PATENT OFFICE.

HOWARD S. KNEEDLER, OF PHILADELPHIA, PENNSYLVANIA.

DESIGN FOR TICKING OR SIMILAR FABRIC.

SPECIFICATION forming part of Design No. 17,626, dated August 9, 1887.

Application filed July 5, 1887. Serial No. 243,440. Term of patent 7 years.

To all whom it may concern:

Be it known that I, HOWARD S. KNEEDLER, a citizen of the United States, and a resident of Philadelphia, Pennsylvania, have invented 5 a new and original Design for Ticking and Similar Woven Fabrics, (Case L. S.,) of which the following is a specification.

My design for ticking and other woven fabrics is fully shown in the accompanying drawings, in which—

Figure 1 is a view showing the general effect, and Fig. 2 is a view drawn to a larger scale and showing the details of the stripes.

My design consists of a wide stripe, A, and 5 a narrow stripe, B, alternating on a ground color, G. The wide stripe A is composed of a number (three in the present instance) of spaced bars, $a a a$, with a ground stripe, g, on each side of the set, and a narrow border, f, o between the main ground G and the ground g of the stripes A. Each bar a consists of a central stripe, 1, of medium shade, with a light stripe, 2, on one side and a dark stripe, 3, on the other. The narrow stripe B consists of a number of spaced bars, b , similar in character 25 and number to the bars a , but narrower in width.

I claim—

The design for ticking and other woven fabrics, said design comprising wide and narrow 30 stripes A and B, alternated on a ground color, the stripe A consisting of a number of spaced bars, a , composed of a central stripe, 1, of medium shade, a light stripe, 2, on one side, and a dark stripe, 3, on the other, ground g on 35 each side of the set of spaced bars a and border stripes f , while the narrow stripe B consists of a number of spaced bars, b , similar in character to the bars a , all substantially as illustrated and described.

In testimony whereof I have signed my name 40 to this specification in the presence of two subscribing witnesses.

HOWARD S. KNEEDLER.
